Specification for Design.

Patented Aug. 2, 1921.

Application filed August 20, 1920. Serial No. 404,920. Term of patent 3½ years.

To all whom it may concern:

Be it known that I, ABRAHAM C. FISHER, a citizen of the United States, and a resident of the borough of Manhattan, in the county, city, and State of New York, have invented a certain new, original, and ornamental Design for Ladies' Handbags, of which the following is a specification.

My new design is illustrated in the accompanying drawing, in which:

Fig. 2 is an end elevation thereof.
Fig. 3 is a perspective of the design.
I claim:
The ornamental design for a lady's handbag, as shown.
